SCOOTER BODY

Charles T. Higgins, 6499 Morris Park Road, and Wellington D. Kreb, 6499½ Morris Park Road, both of Overbrook, Pa. 19151

Filed May 1, 1967, Ser. No. 6,901

Term of patent 14 years

(Cl. D34—15)

FIG. 1.

FIG. 2.

FIG. 4.

FIG. 3.

FIG. 1 is a perspective view of a scooter body showing our new design;

FIG. 2 is a plan view of the scooter body shown in FIG. 1;

FIG. 3 is a front elevational view of the scooter body shown in FIGS. 1 and 2; and

FIG. 4 is a side elevational view of the scooter body.

In FIGS. 1, 3, and 4, the phantom lines show typical wheels which may be attached to the scooter body and are for purposes of illustration only.

We claim:

The ornamental design for a scooter body, substantially as shown and described.
